CLAIM

The ornamental design for an orthotic insole, as shown and described.

DESCRIPTION

FIG. 1 is a bottom perspective view of an orthotic insole, showing our design;

FIG. 2 is a top plan view thereof;

FIG. 3 is a bottom plan view thereof;

FIG. 4 is a right side view thereof;

FIG. 5 is a left side view thereof;

FIG. 6 is a front view thereof; and,

FIG. 7 is a rear view thereof.

The broken lines shown in the drawings represent portions of the orthotic insole that form no part of the claimed design.

1 Claim, 6 Drawing Sheets
